RAZOR

Edward Siegel, New York, N. Y.

Original application October 18, 1932, Serial No.
638,313. Divided and this application January
23, 1934, Serial No. 707,881

21 Claims.

(Cl. 30—48)

This invention relates to hoe-type safety razors, that is, razors which are substantially T-shaped in side elevation, with the staff of the T constituting a handle and with the bar of the T constituting a holder for a removable and renewable thin and highly flexible or ribbon-type blade the opposite sides of which are straight and parallel to present straight and parallel cutting edges. More particularly, the present invention (the subject-matter whereof has been divided out of my copending application Ser. No. 638,313, filed October 18, 1932) relates to that form of previously proposed hoe-type razor wherein the blade holder includes a blade table presenting an elongate laterally curved convexity shaped in such manner that all the lateral curvatures which are intended to act conjointly with the others as blade-flexing ones are identical and aligned longitudinally of the convexity in a direction at an oblique angle to the longitudinal center line of the convexity, so that, as viewed, in top plan, the convexity has substantially parallel sides, but, actually, and side elevationally thereof, one of said sides ascends and the other descends from the same end of the convexity.

These proposals have been made, of course, with the idea that if the blade be suitably positioned and clamped in the holder between an overlying blade cap and an underlying blade table carrying at its top such a convexity as that above described, the blade could be upwardly laterally arched all along the length of the convexity with the longitudinal center line of the blade overlying the longitudinal center line of the convexity, thereby to have the cutting edges of the blade ascend and descend on opposite sides of the razor in substantial parallelism with the opposite sides of the convexity.

A very important object of this invention is to overcome what has been discovered to be a fatal defect in all of these previous proposals. Such defect is an inevitable immediate cracking of the comparatively brittle blade, the first time the holder parts are clamped together above and below the blade, to flex the same as intended, this cracking being due to the kind of elongate positioning or keying means heretofore invariably proposed for holding the blade against bodily shift relative to the convexity preparatory to clamping the blade cap and the blade table tightly together with the blade therebetween. Such a keying means necessarily involves an aperturing of the blade and a coacting key structure carried by a part of the holder; and this blade aperturing, according to the prior art, has

always been in the form of a plurality of apertures spaced along a line coincident with the longitudinal center line of the blade. While this line is straight when the blade is flat, it becomes distorted into a spirally curved one, to correspond with the longitudinal center line of the convexity, when the blade is flexed over the convexity as the result of clamping together the holder parts.

The present invention, although it employs that essential thing, an elongate keying means, very simply yet completely overcomes the fatal defect aforesaid, as the result of providing, in one aspect of the invention, a novel shaping and extension of the blade aperturing, and, in another aspect of the invention, a novel shaping and extension of the coacting key structure carried by a part of the holder. The present invention, therefore, not only provides a new and valuable blade-holder, but also a new and valuable blade.

Another important object of the invention is to provide an improved razor blade which shall not only have an aperturing which forms a part of a novel and valuable keying means as just stated, but which shall also be so constructed, as the result of an auxiliary aperturing of the same, that, while thereby strengthened rather than weakened so far as defeating any tendency thereof toward cracking during flexure thereof is concerned, the cutting edges of the blade will be materially assisted toward easily and safely arranging themselves in a highly desirable if not essential condition when the blade is clamped tightly in a properly shaped holder. This condition of the cutting edges is one such that they are sprung or floated to extend along substantially straight lines over the blade table substantially parallel to the edges of the guard and cap and at opposite sides of convexity.

The invention, and the various objects and advantages thereof, will be clearly understood from an illustrative embodiment of the invention as shown in the accompanying drawing wherein

Fig. 1 is a view in side elevation, showing said embodiment assembled for shaving;

Fig. 2 is a top plan view of such assemblage;

Fig. 3 is an isometric perspective, looking in the direction of the arrow 3 of Fig. 2;

Fig. 4 is a top plan view of the razor blade, removed from the razor, that is, in flat condition;

Fig. 5 is a view showing the top surface of the blade table of the holder in plane development;

Fig. 6 is a view showing the under surface of the blade cap in plane development;

Fig. 7 is a fragmentary detail view, partially in

elevation, and partially in vertical section on the line 7—7 of Fig. 1; and

Fig. 8 is a diagrammatic view explanatory of the behavior of the razor during shaving.

5 Similar reference characters refer to similar parts throughout the several views.

A detailed description will now be given of the razor and razor blade shown in the drawing, with the understanding that nothing therein contained, however particularized or apparently emphasized is indispensable, shall be taken in a limiting sense except as the essentials of the invention are set forth in the appended claims.

10 The razor includes a handle 15, and a holder comprising an elongate blade table 16 and an elongate blade cap 17.

The top surface of the blade table is shaped to present a convexity of such form that when a blade of the type herein shown is flexed over it, 20 that portion of the blade on one side of a median line (A'—X' of Fig. 4) extending obliquely to the cutting edges of the blade, will correspond to a portion of the surface of one cone and the other portion of the blade on the opposite side of said 25 median line will correspond to a portion of the surface of a cone in a position reversed with respect to the first cone. In the application of the blade to the oppositely disposed imaginary conical surfaces it is assumed that the 30 edge 18g is located at the base of one cone, and the edge 18h at the base of the other, those portions of the blade lying between said edges and their respective opposite ends conforming to the surface portions of the imaginary cones 35 over which the blade is flexed.

This convexity covers the entire top of the blade table, including the tops of marginal combs or guard portions 16a and 16b.

40 The under surface of the blade cap 17 is formed to have a concave shaping around its marginal portions surrounding a recess 17a for accommodating certain projections on the top of the blade table 16, later to be described; this concave shaping corresponding to that of the convexity at the 45 top of the blade table.

The upper surface of the blade cap 17 is shaped to have a convex rotundity corresponding to that of the convexity at the top of the blade table 16, except that the lateral curvatures of said 50 rotundity are of less radius than that of said convexity, to gradually thin down the blade cap toward its opposite side edges which are to overlie the blade near its opposite cutting edges.

55 In combination with this razor is employed an elongate highly flexible and very thin or ribbon-type removable and renewable blade 18 having at its opposite sides straight and parallel cutting edges 18a and 18b.

60 The blade table 16, the blade cap 17 and the blade 18 are of properly different widths, such that, after the holder has been tightened up to clamp the blade 18 in the manner intended between the blade table 16 of said holder and the blade cap 17 thereof, the cutting edges 18a and 65 18b of the blade will be so disposed that, as shown in Figs. 2 and 3, said cutting edges will extend substantially parallel with but beyond the sides of the blade cap 17 and substantially parallel with but within the outer limits of the combs 70 16a and 16b of the blade table 16. As seen in Fig. 2, said cutting edges 18a and 18b will extend substantially parallel with each other. At the same time, as seen in Fig. 3, said cutting edges will so extend that one thereof ascends and 75 the other descends from the same end of the

holder, at oblique inclinations to the horizontal, apparently to cross each other at the central point along the length of the holder. These dispositions of the cutting edges of the blade 18 result from the fact that said blade is flexed over the convexity on the top of the blade table 16, with the longitudinal center line of the blade, normally a straight line, directly overlying and following the spiral extension of the longitudinal center line of said convexity. 5

When the razor and blade are thus assembled, the horizontal crest line or longitudinal axis of the holder is contained in the line A—X (Figs. 1 and 2), and this axis is parallel with the horizontal crest line or longitudinal axis of the convexity at the top of the blade table. The latter axis is substantially coincident with the axis of concavity of the under surface of the blade cap 17, and with the axis of curvature of the blade 18; and all these three axes last-mentioned are 20 shown, to simplify the drawing, as contained in a single line A'—X' (Figs. 4, 5, and 6). Further to simplify the drawing, and in aid of brevity, whenever hereinafter the axis A—X or A'—X' is referred to, there will be meant merely that part 25 of line A—X or A'—X' which is contained within the limits of the blade cap, the blade table or the blade, as the case may be.

The axes A—X and A'—X' are, it will be understood, all axes of curvature; and they are the 30 sole axes of curvature of all curved parts of the holder above and including the convexity on the top of the blade table 16, and of the blade. They are, as aforesaid, parallel. They are, moreover, straight lines contained in the same vertical plane 35 through the holder; such plane extending longitudinally of the holder but at an oblique inclination to the longitudinal center line of the holder.

The handle 15 of the razor is an elongate one, depending vertically, with its longitudinal center line 15a projected below a point midway along the line of intersection of said plane with the holder; the handle thus depending from the middle of the holder and being perpendicular to the 40 horizontal axes A—X and A'—X'. 45

In such a razor, when either guard portion 16a or 16b of the holder is placed flat against the face to apply the appropriate blade edge 18a or 18b similar against the face, and when the handle 15 is held vertically, as is most natural, not only 50 are said guard portion and said edge inclined side elevationally of the razor, but the axis A—X of the holder, although horizontal, is inclined toward the face. Further, said guard portion and said edge are inclined to the vertical direction 55 in which the razor will naturally be pulled over the face for the shaving cut. The axis A—X divides the holder into two separate equal portions each a conical vault, but with these vaults 60 symmetrically reversed to have their imaginary 65 apices beyond the two ends of the holder and in prolongations of the axis A—X at points equidistant from the center of the holder. Such a type 70 of razor is the perfect solution, and probably the only even approximate solution, of the problem 75 of providing a razor which, while mounting a single blade having parallel cutting edges, and while mounting such blade to dispose one of these edges on one side of the holder and the other on the other side of the holder, so that either of said edges can be used at will, will 80 naturally or automatically give a wiping shear or true slicing cut, as contradistinguished from the mere chopping or scraping cut heretofore obtainable. By a true slicing cut is meant a single 85 90 95

sweep of the blade edge over the face, in such manner that the direction of sweep is the resultant of two simultaneously performed movements of the blade edge, one laterally thereof and the other longitudinally thereof, and not only therefore diagonal or oblique to the blade edge but also diagonal or oblique to the direction of sweep of the blade itself across the face.

Referring in this connection to Fig. 8, wherefore in the razor now being discussed is seen as in Fig. 1; when during shaving this razor is moved in the usual way over the face by ordinary vertical downpull on the razor handle lengthwise thereof, there is an automatic tendency of the side of the holder and the blade edge applied to the face to have two motions both at an angle to the direction of such pull. That is to say, there is an automatic tendency of these parts to move laterally of said pull and at a considerable if not a right angle thereto,—that is, in the direction of the line L—L, and in the direction of conicity of the conical vault at the side of the holder against the face; and, simultaneously, an automatic tendency of the guard portion and cutting edge against the face to move obliquely relative to the vertical direction of pull, in fact almost perpendicular to the direction C—C of extension of the cutting edge, as indicated by the line D—D. The resultant effect of these two tendencies toward movement in the directions of the lines L—L and D—D, simultaneously exhibited, is a movement of the holder and cutting edge in the direction of the line D—R; giving a true slicing of the hairs of the beard.

By the present invention, this razor is transformed into a practicable and operative one, that is, one wherein the comparatively brittle blade, which must be positioned or keyed in place on one of the holder parts, to prevent bodily shifting of the blade during clamping of the holder parts together to flex the blade, can be thus positioned and keyed, and then flexed in the way required and to the extent required, without cracking of the blade.

Such blade cracking, I have found, can absolutely be prevented if a keying means of the kind now to be described is provided.

The keying means of the present invention includes a particular aperturing of the blade, and for coaction therewith, a particular key structure on the holder.

As to the aperturing of the blade, reference should now be had to Fig. 4, from which it will be seen that the axis A'—X' has an oblique inclination of approximately at least 10° to either cutting edge 18a or 18b of the blade. The chief characteristic of this aperturing is that the blade is provided with a slot 18c having an elongation considerably greater than its width and having a general line of extension including said axis A'—X'. For fully satisfactory results, this slot apparently must have further novel characteristics, as follows: (a) While the slot 18c may or may not be interrupted at about its middle point by a circular or other enlargement such as that shown at 18d, the slot must have sides 18s and 18s' which are straight and parallel from near one end of the slot to near the other end thereof, so that, if the enlargement 18d is incorporated, it is present, as shown, as an interruption merely of the two straight and parallel sides 18s and 18s' of the slot. (b) As to the relations between the axis A'—X' and the longitudinal center line of the slot and the straight and parallel sides of the slot,—either these sides must be so

arranged that they are both equally spaced from said axis while parallel thereto so that the longitudinal center line of the slot lies in said axis; or, preferably, and as shown in Fig. 4, the longitudinal center line of the slot must be at such an oblique inclination to said axis A'—X' that, with each of said straight and parallel sides of the slot prolonged to intersect prolongations of said axis beyond opposite ends of the blade, and with each of the cutting edges of the blade prolonged to intersect the prolongations of the axis, the thus prolonged slot side 18s will intersect the thus prolonged axis at a point V marking the intersection of the latter and the thus prolonged blade edge 18b, the thus prolonged slot side 18s' will intersect the thus prolonged axis at a point V' marking the intersection of the latter and the thus prolonged blade edge 18a, and said points V and V' will be equidistant from the midpoint of the axis A'—X'.

For ideal results, and particularly to facilitate an automatic springing of the cutting edges of the blade to straight line extensions rather than spiral ones when the blade is properly flexed and clamped in such a holder as that herein illustrated and described, yet without cracking the blade, apparently the aperturing of the blade must include, in addition to the slot 18c, two other slots 18e and 18f.

This automatic springing of the cutting edges of the blade to straight line extensions (and which would normally be accompanied, of course, by some torsion and twisting of the blade, however slight), can absolutely safely occur, that is, without the slightest tendency to crack the blade, I have found, if said slots 18e and 18f be extended along substantially the median portions of the frusto-triangular sections of the blade on opposite sides of the axis A'—X'. Incidentally, the fact that the cutting edges of the blade do automatically thus spring to straight line extensions could not have been demonstrated, or, probably, even discovered, prior to the devising of an aperturing of the blade such that the same could be flexed not only in the way and to the extent required to render operable the form of razor to which the present invention relates by permitting this flexure of the blade without cracking thereof but also in a manner to allow the cutting edges of the blade to spring from spiral to straight lines of extension without cracking of the blade.

Whatever be the explanation, I have found that the springing of the cutting edges of the blade to straight lines of extension is automatic, as aforesaid, when the holder parts are well and adequately tightened. One explanation which now seems reasonable is that the blade is so strongly resiliently biased to remain in normal flat extension, particularly along the side marginal portions thereof carrying its cutting edges because these run along the length of the elongate blade, that these side marginal portions of the blade do not allow the holder parts to be manually tightened to an extent quite great enough to make the vertical spacing between the blade cap and the blade table precisely that of the thickness of the blade. A very slight vertical spacing between the blade cap and the blade table below and intermediate the ends of the side margins of the former, such as would be seen only on close scrutiny after these holder parts have been manually tightened up as far as sensibly possible, is apparently enough of a spacing to allow the cutting edges of the blade to spring to straight line extensions.

As to said slots 18e and 18f one on either side of the slot 18c as aforesaid, they must apparently include characteristics additional to those already mentioned, as follows: (a) Each of these slots 18e and 18f must be oppositely tapered, so that each of them is generally of truncated triangular outline. (b) Each of said slots must have a general line of extension at an oblique angle both to the cutting edges of the blade and to the general line of extension of the slot 18c. (c) Both of these slots 18e and 18f must have general lines of extension which are parallel. (d) Each of said slots must have both of its opposite sides straight from near one end to near the other end of the slot. (e) These straight sides of one of said slots must be prolongable to meet a prolongation of the axis A'-X' at the point V, and the straight sides of the other of said slots must be prolongable to meet a prolongation of the axis A'-X' at the point V.

As to the key structure of the holder for co-acting with the blade aperturing 8c, 8e, and 8f, reference should now be had to Fig. 5; such key structure in the present case being shown as carried by the top of blade table 16.

Actual tests have demonstrated that the slot 18c, or an equivalent, and/or the slots 18e and 18f, or equivalents, must be present as true slots, that is, each as an elongate cut-out presenting a single opening from end to end thereof, as contradistinguished from a plurality of round or other localized apertures spaced along a straight line corresponding to the longitudinal center line of a true slot. But, on the other hand, these tests have also demonstrated that the key structure to coact with the slot 18c, in order to provide a keying or positioning means to hold the blade against bodily shifting relative to the convexity on the top of the blade table during blade flexure, need not be a continuous rib or elongate projection extending from end to end of such slot, or even where the slot enlargement 18d is present, a rib-means comprising two rib sections one to one side and the other to the other side of the enlargement 18d and so in effect a single rib filling the slot from end to end thereof except where such rib is interrupted at said enlargement 18d. As the key structure for the slot 18c is here shown, however, the same comprises such an interrupted rib as that last-described; the two rib sections thereof being marked 18c' and 18c'' in Fig. 5. Nevertheless, as just above indicated, cracking of the blade is effectually prevented if the key structure for the slot 18c is otherwise constructed; as my tests have indicated that the paramount thing is the inclusion in the blade of a true slot which, like the slot 18c, has a longitudinal center line which coincides with or is at a very slight oblique angle to the axis A'-X' of the blade. For instance, cracking of the blade is effectually prevented if the slot 18c is laid out in either of the ways hereinabove described, with or without the enlargement 18d, but with the key structure which enters said slot in the form of a plurality of posts (even ones of circular cross-section) spaced along a straight line corresponding to the longitudinal center line of the key structure 18c'-18c'' so that there are two of such posts, at least, at or near the opposite ends of said straight line and desirably, a third such post at or near the midpoint of said straight line.

Any key structure herein referred to or otherwise coming within the invention is, of course, to have the characteristic that it shall coact with

the blade aperturing to hold or brace the blade as devised during flexure thereof. Apparently, an exceedingly small amount of play can be allowed between the blade and such a key structure; but preferably each key-structure component appropriate to the one or more slots of the blade aperturing which is or are to receive such a component nicely fits in the slot appointed to receive the same, at least widthwise thereof at spaced points lengthwise of the slot, and, desirably also, in such manner that the slot is held at its opposite ends against excessive play longitudinally of the slot. That is, if such component is, as last described, composed of a plurality of key-structure elements in the form of posts or the like spaced along the appropriate slot, each of these posts, at the portion thereof engaged by the slot in that stage of the flexing of the blade during which the same is to be acted on by the post as a contributor to a keying instrumentality, will preferably have a dimension perpendicular to the length of the slot only a few thousandths of an inch less than the width of the slot at the location of such post; while said component will include at least two such posts so located and shaped relative to the ends of the receiving slot therefor as to allow of only a few thousandths of an inch play longitudinally of said slot. Similarly, as to the aforesaid rib sections 18c' and 18c'' for the slot 18c, it is pointed out that the convexly rounded or outer ends of these sections and the tapered sides thereof, at the portions thereof where they coact with the sides and ends of the slot 18c as keying instrumentalities during flexing of the blade, are desirably so laid out that the key structure 18c'-18c'' will allow only a few thousandths of an inch or practically no real play as between said key structure and the slot 18c. Wherever hereinafter a snug fit is referred to as between a slot of the blade aperturing and a projection on the holder entering such a slot, there is meant such a fit that the blade during flexing is allowed no more than a few thousandths of an inch of play longitudinally or transversely of its axis A'-X'.

As to key-structure components for the slots 18e and 18f, actual tests have so far failed to satisfy me either that such components are needed, or that they are dispensable; although the indications are that they are exceedingly helpful if not actually necessary, although perhaps only as bracing instrumentalities rather than as auxiliary keying instrumentalities. Nor have these tests fully demonstrated that said key-structure components for the slots 18e and 18f, if they must be employed, can or cannot be each in the form of a plurality of posts or the like spaced along a straight line corresponding to the longitudinal center line of the appropriate slot. Very likely, however, these key-structure components could each be in the form of an elongate projection or rib tapered at its sides and shaped at its ends to have a snug fit within the appropriate slot, but with such rib interrupted substantially midway of its length as is the rib structure 18c'-18c''. As the key-structure components for the slots 18e and 18f are shown, however, each comprises an uninterrupted such rib; that for the slot 18e being marked 18e' and that for the slot 18f being marked 18f'. This is apparently the ideal construction for these key-structure components.

The hereinabove referred to recess 17a in the undersurface of the blade cap 17 is shaped to

accommodate the upper portions of the key structures or key-structure components 18c'—18c'', 18e' and 18f', when the holder parts clamped together with the blade 18 there-between.

5 The holder parts are thus clamped together, and the entire razor assembled, by screwing up the handle 15 tightly against the underside of the blade table 16; the blade cap 17 having a depending threaded stud 17' adapted to pass through an aperture 16' in the blade table 16 and to enter a socket 15' in the top of the handle internally threaded to match the thread on the stud.

Said stud 17' then also acts as a filler for the 15 blade slot 18c between the adjacent ends of the key-structure rib-sections 18c' and 18c'' for that slot. In the present case, said stud completely fills in the space between the adjacent ends of said sections; and the principal reason for incorporating the enlargement 18d of the slot 18c 20 is because, here, the stud 17' happens to be of greater diameter than the width of the slot 18c.

The blade table 16 is herein shown as preferably having, in top plan and in plane development, the outline of a non-rectangular parallelogram, rather than that of say a rectangular parallelogram, and the blade cap 17 is herein shown as having a similar outline, so that each end of the holder will lie as seen in Fig. 1.

30 Where the blade table 16 and the blade cap 17 have the outline aforesaid, the blade 18 desirably has substantially the same outline, as shown; but preferably with the two ends of the blade, which generally extend perpendicular to the axis 35 A'—X', convexly rounded as indicated at 18g and 18h.

As already made plain, the scope of protection contemplated is to be taken solely from the appended claims (except where reference to the 40 foregoing specification may be necessary, in fairness, to save their validity); and these claims are to be interpreted as broadly as is consistent with the prior art.

What I claim as my invention and desire to 45 secure by Letters Patent is:

1. In a hoe-type razor of the kind described, said razor including a ribbon-type elongate blade having straight and parallel sides each presenting a cutting edge, a blade holder comprising a 50 plurality of holder parts between which said blade is received, means for tightening said holder to grip said blade, said holder parts having blade-contacting portions so shaped that when the holder is tightened with the blade correctly set there-in the blade is urged toward lateral flexing about an axis of curvature extending along the blade at an oblique angle to said edges,—the combination, with said blade, said holder parts and said tightening means, of a means for holding the 55 blade in the holder to insure said flexing thereof without cracking the blade; said holding means including a slot in the blade, said slot running lengthwisely of the blade at an oblique angle to a cutting edge thereof and being so disposed on the blade that when the blade is correctly set in the holder said axis of curvature extends through the slot from end to end thereof, and a key structure carried by the holder for entering said slot to maintain the blade correctly set on the holder.

70 2. The razor defined in claim 1, wherein said slot includes straight and parallel sides and has its longitudinal center line so located on the blade that said line coincides with said axis of curvature when the blade is correctly set in the holder 75 by said key structure.

3. The razor defined in claim 1, wherein said slot includes straight and parallel sides each prolongable to meet a prolongation of a different cutting edge of the blade, such meeting points being substantially equidistant from the opposite 5 ends of the blade.

4. The razor defined in claim 1, wherein said slot includes straight and parallel sides each prolongable to meet a prolongation of a different cutting edge of the blade, and wherein prolongations of the axis of curvature of the blade when the blade is correctly set in the holder by said key structure meet said cutting edge prolongations at the points where they are met by prolongations of said slot sides. 10 15

5. The razor defined in claim 1, wherein said holding means also includes a pair of auxiliary slots running lengthwisely of the blade, said auxiliary slots being sidewise offset from the opposite sides of the slot first-mentioned and each tapering oppositely along the length of the blade. 20

6. The razor defined in claim 1, wherein said holding means also includes a pair of auxiliary slots running lengthwisely of the blade, said auxiliary slots being sidewise offset from opposite sides of the slot first-mentioned and each tapering oppositely along the length of the blade, and wherein projections are carried by the holder 25 for engaging said auxiliary slots. 30

7. The razor defined in claim 1, wherein said holding means also includes a pair of auxiliary slots running lengthwisely of the blade, said auxiliary slots being sidewise offset from opposite sides of the slot first-mentioned and each 35 tapering oppositely along the length of the blade; the first-mentioned slot having substantially a uniform width over a major part of its length.

8. The razor defined in claim 1, wherein said holding means also includes a pair of auxiliary slots running lengthwisely of the blade, said auxiliary slots being sidewise offset from opposite sides of the slot first-mentioned and each tapering oppositely along the length of the blade; both the sides of each of said auxiliary slots being 45 prolongable to meet at a common point a prolongation of a different one of the cutting edges of the blade, said points being substantially equidistant from the opposite ends of the blade.

9. The razor defined in claim 1, wherein said holding means also includes a pair of auxiliary slots running lengthwisely of the blade, said auxiliary slots being sidewise offset from opposite sides of the slot first-mentioned and each tapering oppositely along the length of the blade; both the sides of each of said auxiliary slots being 50 prolongable to meet at a common point a prolongation of a different one of the cutting edges of the blade; the first-mentioned slot having substantially a uniform width over a major 55 part of its length and the general direction of extension thereof being such that prolongations of such extension at least approximately pass through said points.

10. A ribbon type elongate blade having 60 straight and parallel sides each presenting a cutting edge, for use in a hoe type razor of the kind described, such blade having an aperture including an elongated slot or series of openings running lengthwisely of the blade at an oblique 65 angle to the cutting edges, said slot or openings and the portions of the blade in alignment with the median line of the slot or openings constituting a line of flexure for the blade when transversely arched by its holder, and said line of 70 75

flexure dividing the blade into two similar parts, each part including the whole of a cutting edge.

11. A razor blade according to claim 10, wherein in said slot includes straight and parallel sides each prolongable to meet a prolongation of a different cutting edge of the blade, and wherein prolongations of said axis of curvature of the blade meet said cutting edge prolongations at the points where they are met by prolongations of said slot sides.

12. A razor blade according to claim 10, wherein in said aperturing of the blade also includes a pair of auxiliary slots running lengthwisely of the blade, said auxiliary slots being sidewise offset from opposite sides of the slot first-mentioned and each tapering oppositely along the length of the blade.

13. A razor blade according to claim 10, wherein in said aperturing of the blade also includes a pair of auxiliary slots running lengthwisely of the blade, said auxiliary slots being sidewise offset from opposite sides of the slot first-mentioned and each tapering oppositely along the length of the blade, each of said auxiliary slots extending at an oblique angle both to the first-mentioned slot and to the adjacent cutting edge of the blade.

14. A razor blade according to claim 10, wherein in said aperturing of the blade also includes a pair of auxiliary slots running lengthwisely of the blade, said auxiliary slots being sidewise offset from opposite sides of the slot first-mentioned and each tapering oppositely along the length of the blade; the first-mentioned slot having substantially a uniform width over a major part of its length.

15. A razor blade according to claim 10, wherein in said aperturing of the blade also includes a pair of auxiliary slots running lengthwisely of the blade, said auxiliary slots being sidewise offset from opposite sides of the slot first-mentioned and each tapering oppositely along the length of the blade; both the sides of each of said auxiliary slots being prolongable to meet at a common point a prolongation of a different one of the cutting edges of the blade, said points being substantially equidistant from the opposite ends of the blade.

16. A razor blade according to claim 10, wherein in said aperturing of the blade also includes a pair of auxiliary slots running lengthwisely of the blade, said auxiliary slots being sidewise offset from opposite sides of the slot first-mentioned and each tapering oppositely along the length of the blade; both the sides of each of said auxiliary slots being prolongable to meet at a common point a prolongation of a different one of the cutting edges of the blade; the first-mentioned slot having substantially a uniform width over a major part of its length, and the general direction of extension thereof being such that prolongations of such extension at least approximately pass through said points.

17. In a hoe type razor of the kind described, and including an elongate blade holder having a plurality of holder parts one of which is a blade table and between which holder parts a ribbon-type elongate blade having straight and parallel sides each presenting a cutting edge is to be received and flexed about an axis of curvature ex-

tending along the blade at an oblique angle to said cutting edges,—the combination, with a blade table shaped at its top to present a laterally curved convexity which is adapted thus to flex the blade to cause one of said cutting edges to ascend and the other to descend from the same end of the holder, said convexity having its longitudinal center line spirally extended but also having a horizontal crest line which is straight, said crest line extending at an oblique angle to the vertical plane including said center line, of a means for keying the blade in the holder to set the blade correctly relative to said convexity, said key means including a key structure extending along said crest line and carried by one of the holder parts.

18. A razor as defined in claim 17, wherein said keying means also includes an aperturing of the blade including a single slot to take said key structure in its entirety.

19. A safety razor having a thin, flexible blade provided with straight and parallel sides each presenting a cutting edge, a handle, clamping means between which the blade is flexed, said clamping means being so shaped that they flex the blade and hold it in cutting position with a portion of the blade at one side of a median line extending obliquely to the cutting edges of the blade corresponding to the surface of a cone and the other portion of the blade on the opposite side of said line corresponding to the surface of another cone reversed with respect to the first, the cutting edges of the blade coinciding with the generatrix of the conical surface to which they conform, said edges lying obliquely with respect to a plane perpendicular to the handle.

20. A safety razor having a holder provided with means for clamping a wafer-type blade, said blade having two parallel cutting edges and having an aperturing extending at an oblique angle to the cutting edges, said aperturing defining a line of flexure for the blade when said blade is held in the clamping means, said line of flexure dividing the blade into two portions each of which, when the blade is in cutting position in the clamping means, lies in a surface corresponding to a portion of the surface of a cone, with the convergence of one conical portion opposite in direction to that of the other.

21. In a razor of the character described, a blade holder having a plurality of parts, one of which is a blade table and between which holder parts a wafer type blade having straight and parallel sides, each presenting a cutting edge is received and flexed about an axis of curvature extending along the blade at an oblique angle to said cutting edges, the blade table being shaped at its top to present a laterally curved convexity adapted to flex the blade to cause one of its cutting edges to ascend and the other cutting edge to descend from the same end of the holder yet maintain said cutting edges on straight lines, said convexity having its longitudinal center line spirally extended but also having a horizontal crest line which is straight, said crest line extending at an oblique angle to the vertical plane, including said center line, and a means for keying the blade in the holder to set the blade correctly relatively to said convexity.
